United States Patent Office

Des. 230,717
Patented Mar. 12, 1974

230,717

AIRCRAFT

Theodore R. Smith, Los Angeles, Calif., assignor to Ted
R. Smith Associates, Inc., Van Nuys, Calif.

Filed Apr. 7, 1972, Ser. No. 242,272

Term of patent 14 years

Int. Cl. D12—07

U.S. Cl. D12—80

Fig. 3A

FIG. 1 is a top plan view of an aircraft showing my new design;

FIG. 2 is a front elevational view thereof; and
FIG. 3 is a side elevational view.

I claim:

The ornamental design for an aircraft, substantially as shown and described.
